UNITED STATES PATENT OFFICE.

CHARLES H. WILSON, OF NEW YORK, N. Y., ASSIGNOR, BY MESNE ASSIGNMENTS, TO
MABEL CRANE BAKER, OF STAMFORD, CONNECTICUT.

APPARATUS FOR GRAPHICALLY PORTRAYING GAMES OR OTHER EVENTS.

1,068,377.

Specification of Letters Patent.

Patented July 22, 1913

Application filed February 26, 1908. Serial No. 417,804.

To all whom it may concern:

Be it known that I, CHARLES H. WILSON, residing at New York city, in the county of New York and State of New York, have 5 invented certain new and useful Improvements in Apparatus for Graphically Portraying Games or other Events, of which the following is a specification.

This invention relates broadly to means 10 for communicating news to the public, and more particularly to improvements in devices such as bulletin boards.

The present invention provides a device for accurately reproducing the progress of 15 athletic events of any character such as baseball, football, cricket, races, such as foot, horse and automobile, or in fact any event wherein it is desired to portray the relative positions and travel of persons or objects or 20 the progress and position of players in a game or the progress and position of an object of play, such as baseball or football.

One of the objects contemplated by my 25 present invention is to provide apparatus of the above character which will accurately reproduce each feature of any event of the above general nature in such manner as will enable the public or those to whose view the device is exposed to readily understand and 30 follow the same.

Another object is to provide, in combination with an appropriate field of the nature 35 of that employed in a particular event or game to be reproduced, an object such as a ball or disk which may, through means substantially invisible to the audience, be shifted to any part of the field in coincidence with the actual movements of the ball or other object used in a game or with the 40 actual movements of competitors engaged in an athletic or other event.

A further object is to provide a device of 45 the above character which will occupy a minimum amount of space wherever employed, and which may be more conveniently operated than have devices of this general character as hitherto devised.

Other objects will be in part obvious and in part pointed out hereinafter.

50 The invention accordingly consists in the features of construction, combinations of elements and arrangement of parts, which will be exemplified in the construction hereinafter described, and the scope of the ap-

plication of which will be indicated in the 55 following claims.

In the accompanying drawings, wherein is shown one of the various possible embodiments of my invention, Figure 1 is a view in front elevation of a device constructed in 60 accordance with one of the various possible embodiments of my invention, Fig. 2 is a similar view of the rear portion thereof showing the actuating mechanism, Fig. 3 is a view in side elevation of the herein disclosed embodiment of the invention, and Fig. 4 is a top plan view of the switches and the controlling mechanism therefor. Fig. 5 is a view in rear elevation showing an arrangement of the parts wherein the main 70 carriage is disposed vertically.

Similar reference characters refer to similar parts throughout the several figures of the drawings.

Referring now particularly to the embodiment of my invention herein disclosed, wherein I have shown the same as adapted to reproduce a baseball game, A, represents a wall which may be constructed in the nature of a bulletin board, the outer surface of 80 which carries the representation of a baseball field. This field, as will be observed, has the various positions occupied by the players appropriately designated by words, letters, numerals or other characters. In the 85 present instance, in addition to the characters which are appropriately designative of the various positions occupied by the players, I have provided a stationary signal at each of the points of the diamond and at 90 the position occupied by a player while at bat. While any approved type of signal may be employed in this relation I preferably employ incandescent electric lamps which are indicated at 1, 2, 3, and 4, respectively, at the diamond points and at 5 in the batter's box. I also provide upon the board various other signals which, in the present instance, are constituted by incandescent 95 electric lamps, the circuits of which are under control of the operator who preferably occupies a position behind the board. These signals operate singly or in combination with other signals to indicate or reproduce plays or other features of the game as 100 will hereinafter be explained.

The lights designated "strikes" may be employed to indicate the number of strikes

thrown by a pitcher to a batsman of the opposing team, the lights designated "balls" similarly indicate the number of balls thrown to said batsman, and the lights designated "out" may be employed to indicate the number of players upon the team at bat that have been declared out by the umpire. I also provide a space at 6 upon which may be exposed the names of the person or persons engaged in umpiring the game. Spaces are also provided upon which may be exposed the names of the teams engaged in the contest as well as the names of the opposing players. Signals in the form of incandescent electric lights are also provided for indicating the particular team at bat and likewise the particular player at bat or on base, and the number of innings played and the half thereof being played is also indicated by appropriate signals which may consist of incandescent lamps arranged to operate as changeable signs. The number of runs scored by each team may also be indicated by stationary signals arranged in the form of changeable signs. Suitably arranged lamps or other signals may be provided which will be appropriately designative of the "run" score by innings as at 7 or any other feature of the game which it may be desirable to portray.

Supported adjacent the field and moved by means hereinafter described is a movable signal which, in the present instance, is constituted by an object formed in simulation of a baseball. This object is indicated at 8, and is shown as resting over the pitcher's "box" ready to be moved to any portion of the field in correspondence with the movement of the ball upon the actual playing field, and thus reproduce in combination with the field and the stationary signals the play upon the actual playing field. In the present instance the movable signal 8 is shown as supported upon a relatively taut, flexible member which extends across the playing field. This member which may consist of a cord, wire or chain constructed of any suitable material may be rendered practically invisible if desired by being painted or colored to correspond with the color of the field. The movable signal will be preferably painted or otherwise colored in contrast to the field so as to be readily distinguishable from a great distance in its movements thereover.

The flexible member 9 in the present instance extends, near either side of the board, through an eye provided in each of arms or members 10 and 11 respectively, which extend about the edge of the board, said arms, at their rear ends, behind the board being attached to a vertically movable carriage 12. Carriage 12 in the present instance is constituted by a frame formed by a pair of horizontally extending, spaced members or rods

13 and a pair of vertically disposed members 14 and 15 respectively, which have their upper ends secured to the ends of rods 13. Each of the vertically disposed members 14 and 15 in the present instance, are provided with peripherally grooved wheels 16 and 17, which travel between vertically disposed, fixed guide rods or tracks 18 and 19 respectively. The carriage 12, therefore, may be moved upwardly and downwardly upon the rear of the board and rides during such movements upon wheels 16 and 17 upon the vertically disposed tracks which operate as guides to maintain the carriage always in a horizontal position. In this illustrative embodiment of my invention, I provide upon the rear face of the board or wall a system of pantograph levers or the like 20 comprising levers 21, 22, 23, and 24. Lever 21 is pivotally connected at 25 and 26 with levers 22 and 23 respectively, and lever 24 is similarly connected to levers 22 and 23 at 27 and 28 respectively. The entire pantograph lever system is supported upon the wall at 29 through a pivotal connection with the lower end of lever 21 as at 30. The opposite end of the system which, in the present instance, is constituted by lever 22 is preferably forked as at 31. The forked members being apertured to receive a pin upon which is journaled a peripherally grooved wheel or trolley 32, said trolley being received between the horizontally extending rods 13 of the movable carriage. It will be understood that lever 20 when actuated will through wheel 32 operate to lift or depress the carriage. The carriage is preferably counterbalanced by means of coil springs 33 and 34.

The ends of the flexible member 9 employed to carry the movable signal after passing through the eyes in pins 10 and 11 are carried inwardly and are attached to the end of lever 22 at its point of connection with wheel 32. It will therefore be understood that any movement of wheel 32 along the horizontally extending rods 13 of carriage 12 will operate to pull the flexible member in either direction thereby causing equal but opposite movements of the movable signal upon its field. In other words the flexible member 9 may be said to constitute a belt which extends about the board and it is adapted to be moved bodily upwardly and downwardly in respect to the field when the carriage is moved in corresponding directions by the pantograph mechanism, said flexible member being moved in the direction of its length when lever 20 moves roller 32 lengthwise of the members 13 of the carriage. From the above it will be obvious that the movable indicator may be moved in vertical or horizontal direction and in any direction which is a component of said horizontal and ver-

tical directions and may be caused to rest over any desired portion of the field.

At the point 28 of pivotal connection of levers 23 and 24 there is provided a movable pointer or indicator which in the present instance is adapted to traverse field 35 formed upon a suitable platform secured to the back of the board, or if desired this field may be provided upon the rear surface of the board. 5 This field is preferably drawn upon a smaller scale than the field upon the front face of the board and may be provided with characters indicating the position of the players upon the actual field and such other indicia as may be desired. In the present instance the fields upon the face of the board and the miniature field are so proportioned and the pantograph mechanism is so constructed that when the pointer or indicator 28 rests upon a 10 given portion of the miniature field the movable signal will occupy a corresponding position upon the larger field, and it will be understood that any movement of the pointer over the miniature field will, through the 15 system of pantograph leverage, operate to lift or depress the carriage 12 or move the roller 32 horizontally between the guide members 13 thereof, thereby moving the signal vertically or horizontally or in a direction which will be a component of movements in vertical or horizontal directions, such movements being always in correspondence to the movement of the pointer over the 20 miniature field. In the present instance, I have shown the movable signal which is constituted by a miniature baseball, as resting over the pitcher's box, the movable pointer of the pantograph mechanism occupying a corresponding position on the miniature 25 field. In order to conveniently operate the pantograph mechanism lever 24 is provided with a handle as at 36, although it should be understood that the operator can manipulate the pantograph mechanism by grasping the 30 same at any point thereof between the point of pivotal support upon the board and its connection with the movable carriage. 35 The leads employed for conducting the electrical current from the source of supply 40 to the lamps may be opened or closed by means of a system of switches herein shown as being mounted upon a switch box 37, which may be supported within the convenient reach of the operator. 45 The switches, in the present instance, are constituted by pivotally mounted members 50 connected with the leads which are adapted to engage with fixed contact points 55, which are also connected with the leads. 60 The switches are preferably operated individually, but means is provided whereby when any number of circuits to the lamps has been closed through an individual manipulation of the switches, all of said 65 circuits may be opened simultaneously. In

order to attain this end, I mount under each system of switches a reciprocating member 40, each of said members having upstanding projections adapted to engage the switches, the construction being such that whenever a switch is moved to such position as will enable it to coöperate with its contact member, the reciprocating member will be moved thereby to such position that it will not interfere with the free movement of the other switches of the system to their contact positions. The reciprocating member is therefore in a position to withdraw simultaneously such switches as have been moved to their contact positions at a single operation. 70 I also provide means whereby all of the switches may be simultaneously moved from their contact positions to open the circuits, such means comprising a master member 41, which is carried upon parallel links 42 and 43, the opposite ends of which are pivoted to a member 44 fixed to the switch box. This master member is set in a position to release the switches whenever one of the reciprocating members is moved by the swinging of a 75 switch to its contact position by means of an upstanding projection 45 upon each of said reciprocating members. It will be understood that any of the reciprocating members which have been likewise moved may be retracted by means of a movement of the master member 41 toward its pivotal connection with the fixed member, and that the parallel links will cause said member to move without changing its relative position with regard to the upstanding portions of the reciprocating switch retractors. 80 Switches, in the form of turn buttons may be provided for individual lamps. 85

To promote clearness of illustration, the 90 wiring of the several lamps employed in this embodiment of my invention has been omitted from the drawings but it will be understood that the signaling system constituted by said lamps will be so wired that 95 any single lamp or set of lamps may be lighted or extinguished through a proper manipulation of the switches by the operator. 100

Having thus described the construction 105 of this embodiment of my invention the operation thereof which should to a large extent be obvious, may now be understood.

The progress of any game or event may be indicated or portrayed by mechanism 110 constructed in accordance with the present invention in various ways which will of course vary with the character of the game or other events which are to be reproduced. In the present embodiment it will be understood that the travel or position of the ball upon the playing field will be indicated by the movement of the miniature ball 8 thereover as controlled by the movement 115 of the indicator 28 of the pantograph mech- 120

125

130

anism 20 which is under the control of the operator who will be in telegraphic or telephonic communication with an observer of the actual game being played or event occurring. It will therefore be obvious that the movable signal may be manipulated to indicate the progress of the ball from one player to another, from one player to any part of said field or to any opposing player. It will also be understood that the miniature ball may be moved in such way as will indicate other features of the game such as strikes, balls, fouls, passed balls, errors, sacrifice hits, and bunts. The said movable signal in its movements to the various positions on the field coöperates with said field and the characters thereon to indicate the above, among other features or plays of the game. The movable signal, moreover, in combination with the stationary signals constituted by the lamps also operates to portray other features of the game as strikes, balls, outs, and stolen bases. The stationary signals also operate to indicate the occupancy of a player on the base line, the scoring of runs, the fact that a player is at bat and the name of the particular player as well as the names of the players upon the bases, and the particular base or bases occupied by players. The number of innings played and the half thereof being played is visually indicated as well, as the particular team at bat through a manipulation of the switch board by the operator, and the runs scored by the opposing teams may be conveniently displayed by the electric signs. For the electric signs employed herein any approved means may be substituted. It will accordingly be seen that I have provided a device of the above character well adapted to attain, among others the several ends and objects of my invention above enumerated in a simple and yet efficient manner. The movable device or signal coöperates with the field to indicate features of the game or the beginning and conclusion of the plays, and the system of stationary signals coöperates with the movable signal to portray other features of the game, as well as the position of the players upon the base lines and the names of the players participating in the play. Every feature of a game may therefore be accurately and graphically portrayed and an observer of the bulletin board will have as thorough an understanding of the game actually being played as would any spectator in attendance at the playing field. While I have shown a system of pantograph levers for affecting the movement of the signal over the field it will be understood that mechanism of other types may be employed in this relation without departing from the spirit or scope of the present invention, and that the herein described mechanism may be differently arranged or sup-

ported upon the board. The vertically movable carriage may also be changed so as to move horizontally and the flexible member which carries the movable indicator may extend vertically instead of horizontally across the face of the board. This latter arrangement would be advantageous in that the counter-balancing means for the carriage could be omitted, for instance, such as shown in Fig. 5, and where the appropriate parts are similarly numbered as in the other figures. In the present invention, the counter-balancing means is so adjusted that the movable indicator into whatever position it has been moved will automatically return to the position shown when the operating handle of the pantograph mechanism is released by the operator.

It will be obvious that the herein described mechanism is possessed of great adaptability and may be employed singly or in combination with other similar constructed organizations to portray a great variety of events. Thus, by substituting road maps for the ball-field or other field an automobile race may be accurately portrayed.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

It is also to be understood that the language used in the following claims is intended to cover all of the generic and specific features of the invention herein described and all statements of the scope of the invention, which, as a matter of language, might be said to fall therebetween.

Having thus described my invention, what I claim as new and desire to secure by Letters Patent is:

1. In apparatus of the class described, in combination, means carrying a representation of a field, a signal comprising a movable object arranged adjacent said field, a flexible member extending in opposite directions from the movable object and across said field and forming a support for said movable object, and means for moving said flexible member whereby said movable object may be carried to any portion of said field.

2. In apparatus of the class described, the combination with a suitable field, of a movable indicating device arranged adjacent said field, a flexible support for said indicating device extending in opposite directions therefrom and across said field, and means adapted to move said flexible support bodily in a lateral direction and simultaneously in an endwise direction whereby the said indi-

cating device may be moved to any portion of said field.

3. In apparatus of the class described, in combination, a wall carrying the representation of a field, a movable indicator arranged adjacent said wall, a flexible member extending around the wall and forming a support for said indicator, and means operable from a position behind said wall, adapted for moving said flexible support bodily in a lateral direction and in an endwise direction, whereby said indicator may be moved to any part of said field.

4. In apparatus of the class described, the combination with a wall provided with the representation of a field, of a movable indicator arranged adjacent said field, a flexible supporting member for said movable indicator stretched across said field, a movable member supporting said flexible member and adapted to move the same bodily with it, and a device for moving said flexible member endwise with respect to said movable member.

5. In apparatus of the class described, the combination with a wall provided with the representation of a field, a movable indicator arranged adjacent said field, a flexible member extending across said field, a suitably guided support for said flexible member mounted for movement behind said wall, and means for moving said support whereby said flexible member will be moved in one direction with respect to said field, and for moving said flexible member with respect to said movable support whereby that portion thereof which carries the indicator will be moved in a different direction upon said field.

6. In apparatus of the class described, the combination with a wall provided with the representation of a suitable field, a movable signaling device arranged in proximity with said field and adapted to be moved therewith, a flexible supporting member extended across the field and forming a support for said signaling device, a movable carriage which supports said flexible member, means for moving said carriage whereby said flexible member may be moved with relation to said field, said means moving said flexible member independently of the carriage.

7. In apparatus of the class described, in combination, a wall provided with the representation of a field, a flexible member extended across said field, an indicating device mounted upon said flexible member, a movable carriage for supporting said flexible member, and a lever for moving said carriage whereby said flexible member and said indicating device will be moved with respect to the field, said lever being adapted to move said flexible member independently of a movement of the carriage.

8. In apparatus of the class described, in

combination, a wall provided with a suitable field, a movable indicating member, a flexible support for said indicating member stretched across the field and supported at opposite sides thereof, and means for changing the disposition of said flexible member with respect to said field whereby said indicating member may be moved with respect to said field.

9. In apparatus of the class described, in combination, a wall provided with a representation of a field, a movable indicating member, a flexible support for said indicating member stretched across the field, means for supporting said flexible support arranged at oppositely disposed points of said field, and means for moving said last mentioned means whereby said flexible support will be moved with respect to said field and the position of said indicating member will be changed with respect to said field.

10. In apparatus of the class described, in combination, a wall provided with the representation of a field, a flexible member extended across said field, an indicating member positioned upon said flexible member, a movable carriage suitably supported and guided behind said wall, means for connecting said carriage with said flexible member, means for moving said carriage whereby said flexible member will be moved laterally over said field, and also for moving said flexible member in an endwise direction on the carriage.

11. In apparatus of the class described, in combination a wall provided with a suitable field, a member extended across said field, an indicating device supported by said member, a support for said first mentioned member arranged at oppositely disposed points of said field, means for moving said supports and for moving said first mentioned member independently of said support, whereby said indicating member will be moved with relation to said field.

12. In apparatus of the class described, in combination a wall provided with the representation of a field, a flexible member extending across said field and terminating behind said wall, an indicating member arranged in proximity with said field and mounted upon said flexible member, a movable carriage for supporting said flexible member arranged behind said wall, guides for said movable carriage, and means for moving said carriage whereby said flexible member and the indicating member carried thereby will be moved with respect to said field, said last mentioned means being also adapted to move said flexible member independently of a movement of the carriage.

13. In apparatus of the class described, in combination a wall provided with a field, a carriage arranged for movement behind said field, a pair of arms connected with

- 5 said carriage and extending therefrom to a position in front of said field, a flexible member extended between said arms and movable endwise with respect thereto, an indicating device mounted upon said flexible member, and means for moving said carriage whereby said flexible member and the indicating device carried thereby will be moved over said field, said last mentioned member being also adapted to move said flexible member independently of a movement of said carriage.
- 10 14. In apparatus of the class described, in combination a wall provided with a representation of a field, a movable signal, a traveling member on the other side of said wall, a flexible support for said signal stretched across said field, and terminating in said traveling member, and means for supporting said flexible support and for guiding said traveling member, whereby said means may be moved bodily or said traveling member may be moved with relation to said means to impart different movements to said signals.
- 15 15. In apparatus of the class described, in combination a wall provided with a representation of a field, a flexible member extended across said field, an indicating signal positioned upon said flexible member, a movable carriage suitably supported and guided behind said wall, and means for connecting said carriage with said flexible member whereby the latter may be moved with relation to said carriage or said carriage may be moved bodily to impart different movements to said signals.
- 20 16. In apparatus of the class described, in combination a wall provided with a suitable field, a supporting member capable of translation, a member extended across said field and supported by said first member, and an indicating device supported by said extended member, said extended member being movable independently of the movement or position of said first member.
- 25 17. In apparatus of the class described, in combination a wall provided with a suitable field, a carriage for movement behind said field, a pair of arms connected with said carriage and extending therefrom to a position in front of said field, a flexible member extended between said arms and movable with respect thereto, and an indicating device mounted upon said flexible member, said flexible member being movable independently of the movement or position of said carriage.
- 30 18. In apparatus of the class described, in combination a bulletin board provided with a plurality of stationary signals and having the representation of a field thereon, a carriage arranged for movement behind said field, a pair of arms connected with said carriage and extending therefrom to a position in front of said field, a flexible member extended between said arms and movable with respect thereto, and an indicating device mounted upon said flexible member, said flexible member being movable independently of the movement or position of said carriage.
- 35 19. In a device of the class described, a movable signal adapted to represent the movement of one of the factors in an athletic or other event, and means for the actuation of said signal comprising a flexible support for said signal operable to cause the movement of said signal and a movable carriage operable to cause the translation of said flexible support whereby the individual operation of either said support or said carriage will cause a simple movement of said signal and the simultaneous operation of both said support and said carriage will cause a compound movement of said signal.
- 40 20. In apparatus of the class described, in combination a wall provided with a field, a signal movable over said field, and a bodily movable supporting means for said signal comprising an endwise movable member upon which said signal is mounted, and a supporting member for said endwise movable member suitably guided for translation, whereby an individual operation of either of said members will cause a simple movement of said signal and the simultaneous operation of both will cause a compound movement of said signal.
- 45 21. In apparatus of the class described, in combination a wall provided with a field, a signal movable over said field, and a bodily movable carriage for said signal, comprising an endwise movable member upon which said signal is mounted and a bodily movable frame upon which said endwise movable member is mounted, said endwise movable member and said bodily movable frame being suitably guided whereby the individual operation of either of said members will cause a simple movement of said signal and the simultaneous operation of both will cause a compound movement of said signal.
- 50 22. In apparatus of the class described, in combination, a wall provided with twin representations of a field, a movable indicator arranged adjacent one of said fields, a flexible member extending across said last mentioned field, a suitably guided support for said flexible member mounted for movement behind said wall, means for moving said support whereby said flexible member will be moved in one direction with respect to said last mentioned field and for moving said flexible member with respect to said movable support whereby that portion thereof which carries the indicator will be moved in a different direction upon said field, said means being connected at one
- 55 60 65 70 75 80 85 90 95 100 105 110 115 120 125 130

point to said flexible member, and adapted to travel at another point over the other of said fields, and an operating member connected to said means at any portion thereof.

5 23. In apparatus of the class described, the combination with a member provided with twin representations of suitable fields, of a movable indicator arranged adjacent one of said fields, a flexible support for said indicator, a movable carriage with which said flexible support is connected, means for moving said carriage whereby said support and the indicator carried thereby will be moved with relation to said last mentioned field, said means being connected at one point to said flexible member and adapted to travel at another point over the other of said fields, and an operating member connected to said means at any portion thereof.

10 24. In apparatus of the class described, the combination with a wall provided with twin representations of a field, of a flexible member extended across one of said fields, and terminating behind said wall, an indicating member arranged in proximity with said field and mounted upon said flexible member, a movable carriage for supporting said flexible member arranged behind said wall, guides for said movable carriage, means for moving said carriage whereby said flexible member and the indicating member carried thereby will be moved with respect to said last mentioned field, either separately or simultaneously, said means being connected at one point to said flexible member and adapted to travel at another point over the other of said fields, and an operating member connected to said means at any portion thereof.

15 25. A bulletin board comprising the combination of an indicator in front of the board, mechanism in the rear of the board, an endless flexible connection between said indicator and said mechanism extending beyond the board so as to move said indicator to any portion of the board.

20 26. In an apparatus of the character described, a board having an unbroken surface with a field representation thereon, a ball indicator adapted to play over the field, and means upon the rear of said board coöperating with said indicator to move the same over the unbroken surface of the field, said means including a slidable support mounted on said board, and an operating device movable upon said support and operatively connected with the ball indicator.

25 27. In apparatus of the character described, the combination of a board having upon one surface field representations, a ball indicator upon said surface, and means for moving the ball in longitudinal and transverse directions relative to the field comprising a member connected with the ball indicator and extending over the front surface

of the board to a point beyond the field, a slidable support to the rear of the field, a movable device on the support for operating the member connected with the ball indicator.

30 28. In a device of the class described, a board having a field, an indicator adapted to play over the field, operating mechanism for the indicator which is pivotally mounted upon the rear of the board, and an endless cord connection between the indicator and the operating mechanism which extends beyond the bounds of the field.

35 29. In a device of the class described, a board having a field, an indicator adapted to play over the field, operating mechanism for the indicator which is pivotally mounted upon the rear of the board and which extends from the indicator in a plane substantially parallel to the plane of the board, and connecting means between the indicator and the operating mechanism which is carried by the operating mechanism comprising a flexible member extending from the indicator in opposite directions.

40 30. In a device of the class described, a board having oppositely facing fields, pivotally supported mechanism comprising relatively movable parts adjacent one of said fields, an indicator positioned adjacent the other of said fields, and connecting means between the indicator and one of the relatively movable parts of said mechanism including an endless flexible member extending around the board.

45 31. In a base ball bulletin, the combination with a field board, of a pivoted frame in rear thereof, an adjustable device supported by the frame, an indicator arranged in front of the field, and flexible connections between the indicator and the adjustable device comprising flexible connections extending in opposite directions from the indicator and connected respectively to the said adjusting device.

50 32. In an apparatus of the character described, the combination of a field representation, an indicator, a flexible support for the indicator extending in one direction beyond the bounds of the field, an auxiliary flexible support for the indicator extending in an opposite direction beyond the bounds of the field, bodily movable actuating means at the rear of the field for moving said flexible support, and associated mechanism whereby the indicator moves an increased distance over the field relative to said means.

55 33. In an apparatus of the character described, the combination of a board having thereon a field representation, an elongated guide, a device mounted on the guide for movement, a guide surface for the device, an indicator to play over the field representation, and connections between the device and indicator whereby a relatively short

movement of the device will result in an increased movement of the indicator.

34. In an apparatus of the character described, the combination of a field representation, a movable supporting frame, an indicator to move over the field representation and endwise relative to the frame, an actuating device mounted to move back and forth, and means whereby the device and indicator move at different speeds.

35. In an apparatus of the character described, the combination of a field representation, an indicator to move thereover, a flexible member connected to the indicator and projecting in one direction beyond the bound of the representation, an auxiliary flexible member connected to the indicator and projecting in an opposite direction beyond the bounds of the representation, and a bodily movable operating member operatively connected to both flexible members for moving the indicator a different distance relative to the operating member, and a guide surface of the operating member.

36. In an apparatus of the character described, a field representation, an indicator to move thereover, a support connected at one end to the indicator and projecting in one direction beyond the bounds of the field, an auxiliary support connected to the indicator and projecting in an opposite direction beyond the bounds of the field, and a bodily movable member having associated means engaging said supports for moving the indicator in the same direction as the movable member different distances during the same time.

37. In an apparatus of the class described, the combination with a board member, of a movable frame member, an actuating device slideable longitudinally on the frame member, an indicator arranged at the front of the board, and means interposed between the indicator and the frame and associated with said actuating device whereby upon the movement of the actuating device the indicator is moved a distance greater than the distance of the movement of the actuating device.

38. In a bulletin board, the combination of a wall having on one side a representation, an indicator to move over the representation, a flexible member connected to the indicator and extending beyond the representation and to the rear of the board, and means at the rear of the board for moving the indicator over said representation, in-

cluding a supporting member movable in one direction, and an operating means movably mounted on the supporting member for movement in a different direction, said flexible member being operatively connected to 60 said operating means.

39. In an apparatus of the class described, in combination, a wall provided with the representation of a field, a movable signal, a traveling member on the other side of said wall, a flexible support for said signal stretched across said field, and terminating in said traveling member, and means for supporting said flexible support and for guiding said traveling member, whereby 70 said means may be moved bodily or said traveling member may be moved with relation to said means to impart different movements to said signal.

40. In an apparatus of the character described, the combination of a board, having a field representation, of a flexible member extending around the board, an indicating device operatively associated with the flexible member, and movable means for supporting the flexible member loosely to permit an endwise movement of the latter on the former, and whereby upon the movement of the movable means the indicating device will move therewith.

41. In an apparatus of the class described, in combination, a vertically extending wall having a field representation on the front surface thereof, a flexible member stretched entirely across said field, an indicating device carried by said flexible member, and means for moving said flexible member whereby said indicator may be moved to any part of said field.

42. In a ball bulletin board, the combination of an upright member having a ball field representation on the front surface thereof, an indicator to move over the field representation, a flexible means extending in different directions from the indicator 100 to points beyond the field representation, and means operatively associated with said flexible means at points beyond the field representation and operable from the rear of the upright member.

In testimony whereof I affix my signature, in the presence of two witnesses.

CHARLES H. WILSON.
